ABSTRACT OF THE DISCLOSURE

A process for converting aliphatic olefins, such as, octene-1, heptadecene, etc., to carboxylic acids, wherein the olefin is oxidized with a peracid, such as, performic, peracetic, persuccinic, etc., in the presence of a ruthenium catalyst, such as, ruthenium dioxide, ruthenium trichloride, etc., and a small amount of an organic or inorganic base, such as, amines, alkali metal and alkaline earth metal hydroxides, carbonates, etc.

BACKGROUND OF THE INVENTION

The present invention relates to a process for the catalytic oxidation of olefins to produce carboxylic acids. More specifically, the present invention relates to a process for the catalytic oxidation of aliphatic olefins to produce carboxylic acids in the presence of a ruthenium catalyst, a peracid oxidizing agent and a small amount of a base.

Fatty acids have heretofore been used commercially for the manufacture of synthetic lubricants and soaps. Consequently, the market for such fatty acids has generally exceeded the ability of industry to supply these materials from their sources. There is therefore a substantial demand for such fatty acids, particularly those having long carbon chains.

In the past, numerous processes have been developed for the production of fatty acids from various related materials. In one such process, the various alcohols, such as, primary alcohols, were treated with an oxidizing agent in the presence of a catalyst, such as, ruthenium to produce the corresponding fatty acids. In these processes, the conversion to fatty acid is generally quite low. Similarly, fatty acids have heretofore been produced by the catalytic or noncatalytic oxidation of various olefins, usually primary olefins and cyclic olefins. In one such process, as disclosed in U.S. Pat. 2,585,129, a primary olefin is oxidized with hydrogen peroxide in the presence of peracetic acid to produce the corresponding saturated dihydroxy hydrocarbon. Thereafter, the dihydroxy compound is selectively oxidized with periodic acid to cause cleavage between the acid contiguous hydroxylated carbons and thereby form a fatty aldehyde which, in turn, is further oxidized with peracetic acid to form the corresponding fatty acid. Obviously, this multi-step process is time-consuming and, in addition, the yield of fatty acid is quite low. In a similar process, as set forth in West German Offenlegungsschrift 2046034, an aliphatic or cyclic olefin is reacted with an oxidizing agent in the presence of a ruthenium catalyst. However, it has been found by carrying out the preferred technique of the German publication that a number of byproducts are produced, such as diols, diol monoacetates, and diol diacetates and therefore, the production of the fatty acid is low. Accordingly,

these prior art processes have not been as successful as desired, to the extent that substantial amounts of starting materials are wasted or are converted to other compounds which either must be discarded or oxidized in a multi-step process to produce the desired fatty acids.

It is therefore an object of the present invention to provide an improved process for converting aliphatic olefins to fatty acids. Another object of the present invention is to provide an improved process for producing fatty acids from aliphatic olefins wherein a high selectivity to fatty acid is obtained. Another and further object of the present invention is to provide an improved process for the conversion of aliphatic olefins to fatty acids in the presence of a ruthenium catalyst, peracid oxidizing agent and a base. Another and further object of the present invention is to provide an improved process for the conversion of aliphatic olefins to fatty acids in the presence of a ruthenium catalyst, a peracid oxidizing agent, a base, and an inert organic solvent.

These and other objects and advantages of the present invention will be apparent from the following detailed description.

SUMMARY OF THE INVENTION

The process for the conversion of olefins to fatty acids comprising contacting an aliphatic olefin with a peracid oxidizing agent in the presence of a ruthenium catalyst and a base.

DETAILED DESCRIPTION OF THE INVENTION

The oxidation process of the present invention causes a cleavage between the contiguous double bond carbons of the aliphatic olefin to form two moles of acids in accordance with the following equation:

wherein R_1 and R_2 may be alike or different straight or branch chain alkyl radicals, aryl radicals, alkaryl radicals, aralkyl radicals, or hydrogen. Preferred R_1 and R_2 alkyl radicals contain from 2 to about 40 carbon atoms at preferably about 2 to 20 carbon atoms, such as ethyl, butyl, octyl and decyl; preferred R_1 and R_2 aryl radicals include phenyl and naphthyl; suitable R_1 and R_2 aralkyl radicals include phenylethyl and naphthyl-butyl wherein the alkyl portion of the aralkyl radical may contain from 1 to about 6 carbon atoms; preferred R_1 and R_2 aralkyl radicals include tolyl and methylnaphthyl and include alkyl substituents of 1 to about 6 or more carbon atoms.

The process may be employed to oxidize a wide variety of aliphatic olefins to yield high volumes of the desired acids. Where the term "aliphatic olefin" is utilized herein, it is meant to include any compound having one or more double bonds in a straight chain either in a straight chain compound or as a substituent of a branched chain or cyclic compound. Generically, the olefins which may be employed include 2-olefins, (ethylenically-unsaturated olefins) vinylidines and dienes having about 2-40 C's. Specific examples of suitable materials include ethylene, propylene, hexene-1, isobutylene, 4-methylhexene-1, decene-1, 1-5-hexenediene, 6-propyl decene-1, dodecene-1, dodecene triene-1, 4, 8, 2-butyl-1-octene, pentadecene-1, hexadecene-1, eicosene, octadiene, pentacosene-6, non-

acosene-3, hexatricotene-1, pentacontene-15, 4-ethylcocene-2, styrene, 3-methyl-styrene, tetraphenylethylene, vinylnaphthalene, vinylanthracene, 4 butyl-1 vinylnaphthalene, 2,7-diphenyldodecene-3, hexane-1, octene-1, decene-1, dodecene-1, tetradecene-1, 8-heptadecene, isomers of decene, dodecene, tetradecene, hexadecene and eicosene, vinylcyclohexane, butadiene-1,3, and alkyl-substituted butadienes.

Normally between about 10 to 80% by weight of olefins should be present.

Where the term "peracid" is utilized in accordance with the present invention, this term is meant to include materials as defined in "The Condensed Chemical Dictionary," 6th Edition, Reinhold and Company, 1956. In accordance with this definition, peracids are derivatives of hydrogen peroxide the molecules of which contain one or more directly linked pairs of oxygen atoms, —O—O—. These peracids do not include permanganic, perchloric, and periodic acids. Suitable peracids for use in accordance with the present invention are peracetic, performic, perphthalic, persuccinic, persulfuric, perboric, trichloroperacetic, trifluoroacetic, perbenzoic, m-chlorobenzoic, p-nitrobenzoic, etc.

A large amount of the peracid should be present in the reaction mixture. By way of example, this amount should be between about 1 to 105% by weight of the olefin. A preferred amount of peracid is between about 50 to 100% by weight.

The catalyst utilized in accordance with the present invention is ruthenium metal or an organic or inorganic ruthenium compound. Any organic or inorganic ruthenium salt having an anion which does not unduly restrict the formation of the desired products by an extraneous side reaction can be utilized as a catalyst. Salts of fatty acids having up about four carbon atoms are preferred organic salts. Examples of such compounds include ruthenium formate, acetate, propionate or butyrate. Inorganic salts in general and simple inorganic salts in particular constitute a highly preferred class of ruthenium-containing catalysts, such as, sulfides and oxides of ruthenium. In addition to the above, organo-metallic compounds, such as, bis (cyclopentadienyl) ruthenium and ruthenium carbonyls, such as, $\text{Ru}(\text{CO})_5$, $\text{Ru}_2(\text{CO})_9$, $(\text{Ru}(\text{CO})_4)_3$, $\text{Ru}(\text{CO})_X$, wherein X is chlorine, bromine or iodine, may also be employed as catalysts. A wide variety of ruthenium chelates are also applicable in the present process. Preferred chelates have a donor atom selected from the group consisting of Group V-V and Group VI-B elements of the Periodic Table. Chelating agents having a donor atom selected from the class consisting of nitrogen and oxygen are quite effective. Triamines, tetra-amines and oximes comprise a preferred class of chelating agents having nitrogen as a donor atom. Dibasic carboxylic acids are also a preferred class of chelating agents having an oxygen as a donor atom. Thus, chelates, derived from well-known chelating agents, such as, salicylic acid, 2-acetyl oxime, 2-benzoin oxime, dimethylglyoxime, acetylacetone, amino-acetic acid, oxalic acid, diethylenetriamine, triethylene-tetraamine, malonic acid, and the like can be employed, Illustrative examples of such chelates include

$\text{Na}_3[\text{Ru}(\text{C}_2\text{O}_4)_3] \cdot 6\text{H}_2\text{O}$, $\text{K}_3[\text{Ru}-(\text{malonate})_3] \cdot 5\text{H}_2\text{O}$, tris (ethylenediamine) ruthenium III, and the like.

As a general rule, the amount of ruthenium catalyst present in the reaction mixture should be between about 0.0001 and 1.0% by weight of the olefin. Preferably, the ruthenium catalyst is present in amounts between about 0.0001 and 0.001% by weight.

Suitable bases in accordance with the present invention may include any organic or inorganic base which does not interfere with the main reaction. Organic bases, such as, primary, secondary, and tertiary organic amines such as triethylamine and pyridine are suitable. Metal salts of fatty acids selected from metals of Group I-A and Group II-A of the Periodic System are preferred wherein the

fatty acid has up to about 4 carbon atoms. Inorganic bases, such as, Group I-A and Group II-A metal hydroxides, carbonates, phosphates and the like are particularly preferred. The mole ratio of peracid to base should be between about 4 to 1 and 100 to 1. Preferably, the peracid to base ratio should be between about 10 to 1 and 50 to 1 and, in most cases, should range between about 25 to 1 and 40 to 1.

The process is generally carried out in the presence of an organic solvent. Specifically, any inert solvent which is not susceptible to oxidation can be utilized. Paraffinic hydrocarbons having about 5 to 30 C's, halogenated hydrocarbons with about 4 C's, esters with about 2 to 20 C's, etc., such as, pentane, hexane, heptane, etc. are preferred. Dichloromethane, ethyl acetate, and trifluoroacetic acid are also useful.

Suitable amounts of solvent are from about 25 to 90% by weight of the reaction mixture and preferably, between about 25 and 75% by weight.

In the event that the peracid or the catalyst is not readily miscible with the solvent, agitation may be advantageously employed.

The process of the invention described herein is generally carried out at the reflux temperature of the solvent and under atmospheric pressure. However, when olefins having a lower boiling point than the solvent are employed, it is preferable to carry out the reaction under pressure. Any pressure above atmospheric may be utilized. However, pressures within the range of about 50 to 500 p.s.i.g. are preferred.

The following detailed examples illustrate the operation of the present invention.

EXAMPLE 1

Octene-1 (11 g.), $\text{RuCl}_3 \cdot 3\text{H}_2\text{O}$ (0.05 g.), and hexane (100 ml.) were placed in a one liter, 3-neck flask equipped with an addition funnel, a thermometer, a mechanical stirrer and a reflux condenser. The reaction mixture was stirred to obtain a homogeneous dispersion of the ruthenium compound in the organic solvent. At this time, a solution of 2.5 g. sodium acetate in 100 g. of 40% by weight peracetic acid was added. An exothermic reaction took place. The peracid was added in a way such that the mixture was kept refluxing at about 64° C. After the addition was completed, the reaction mixture was allowed to reflux for an additional hour and then cooled to room temperature. The reaction mixture formed two phases which were then separated. The aqueous phase acidified to a pH of 1 with hydrochloric acid, was then extracted with two volumes of 100 ml. of hexane. The combined hexane fractions were washed with 100 ml. of water to secure complete elimination of the acetic acid. The hexane layer was concentrated to a residue under reduced pressure. The residue was analyzed for fatty acids and found to contain 1.0 g. hexanoic acid, 10.3 g. heptanoic acid and 0.5 g. octanoic acid. The molar selectivity to total acids was 93.0%.

EXAMPLE 2

The procedure of Example 1 was repeated except that the ruthenium trichloride was replaced by ruthenium dioxide. In this particular example, the molar selectivity to total acids was 90%.

EXAMPLE 3

The experimental procedure of Example 2 was repeated except that sodium acetate was not added to the peracid. The molar selectivity in this case was found to be 76.4%.

EXAMPLE 4

The experimental procedure of Example 2 was repeated except that sodium acetate was replaced by sodium carbonate. The molar selectivity in this case was found to be 95.5%.

These, as well as additional examples made under varying conditions, are summarized in Table I.

^a German Patent publication.^b Sodium carbonate was used in the place of sodium acetate.^c Peracetic acid.^d Sodium acetate.

From the above example, it is clear that the runs made utilizing a base are superior to those made under the conditions of German patent publication 2,046,034 where no base was employed.

Runs were also made to determine the effect of an added base on the conversion of cyclic olefins, having double bonds in a ring structure, to acids.

EXAMPLE 14

Following the procedure of Example 1, 8.2 g. of cyclohexene, 0.05 g. of RuCl₃, 100 ml. of hexane, 100 g. of 40% peracetic acid and 2.5 g. of sodium acetate were utilized. A yield of 74.3% by weight was obtained.

EXAMPLE 15

Example 14 was repeated except that no sodium acetate was utilized. In this case, the yield was 71.2%.

It is obvious from Examples 14 and 15 that the addition of a base had no significant effect on the reaction when the double bond is present in a ring structure.

While specific materials and specific techniques have been disclosed herein, it is to be understood that these recitations as well as the specific working examples are illustrative only and that numerous variations and modifications of the process will be apparent to one skilled in the art. Accordingly, the present invention is to be limited only in accordance with the appended claims.

I claim:

1. In a process for the catalytic oxidation of an aliphatic olefin to carboxylic acids with a peracid oxidizing agent in the presence of ruthenium catalyst the improvement which comprises adding to the reaction mixture an alkali metal salt of a lower fatty, acid, or carbonate.

2. A method in accordance with Claim 1 wherein the

aliphatic olefin has at least one double bond in a straight chain.

3. A method in accordance with Claim 1 wherein the aliphatic olefin has a plurality of double bonds in a straight chain.

4. A method in accordance with Claim 1 wherein the aliphatic olefin is an alpha-olefin.

5. A method in accordance with Claim 1 wherein the ruthenium catalyst is ruthenium metal.

6. A method in accordance with Claim 1 wherein the ruthenium catalyst is an organic ruthenium compound.

7. A method in accordance with Claim 1 wherein the ruthenium catalyst is an inorganic ruthenium compound.

8. A method in accordance with Claim 1 wherein the reaction mixture additionally contains an inert solvent.

9. A method in accordance with Claim 8 wherein the alkali metal salt is present in a ratio of peracid oxidizing agent to alkali metal salt between about 4 to 1 and 100 to 1.

10. The process in accordance with Claim 1 wherein the alkali metal salt is sodium acetate.

11. The process in accordance with Claim 1 wherein the alkali metal salt is sodium carbonate.
